UNITED STATES PATENT OFFICE

WILLIAM H. WATTS AND ELMER J. CURRIE, OF HOULTON, MAINE

INSTRUMENT FOR OUTLINING INSCRIPTIONS ON MONUMENTS OR THE LIKE

Application filed June 20, 1929. Serial No. 372,353.

This invention relates to the art of inscribing monuments and the like, and has for one of its objects to provide a novel, simple and inexpensive instrument through the medium 5 of which an inscription may be easily and quickly outlined or traced on a monument or the like, whereby to insure the cutting of letters and figures of correct formation and the uniform spacing of the letters, figures and 10 words, and whereby to materially reduce the time and work involved in cutting inscriptions.

To attain the foregoing and other objects, the nature of which will appear as the description proceeds, the invention comprehends the provision of an instrument of the character stated which shall embody blank letters and figures from which the inscription will be made up, and a clamp adapted to 20 hold the letters and figures in inscription forming relation and adapted to permit the letters and figures to be held in such position as to enable them to be easily and quickly traced or outlined on a monument or the like. 25 The invention also comprehends the provision of an instrument of the character stated wherein the clamp shall be of such construction as to enable the required letters or figures or both to be readily assembled and secured therein in proper spaced relation.

The invention is hereinafter more fully described and claimed, and illustrated in the accompanying drawing, wherein:—

Figure 1 is a view in front elevation of an 35 inscription tracing or outlining instrument constructed in accordance with my invention;

Figure 2 is a sectional view taken on the vertical planes indicated by the line 2—2 of Figure 1; and

Figure 3 is a top plan view of the instrument.

The instrument comprises blank letters and figures. One letter and one figure are shown, and they are designated 1 and 2, respectively. 45 The characters 1 and 2, which may be of any size and of script, Gothic or other type, may be made from light sheet metal or any other suitable material, and are provided at their lower ends with extensions or tongues 3 to 50 permit them to be secured in a clamp 4.

The clamp 4 is of elongated rectangular formation, and it may be made of metal or other suitable material and of any desired or required length. The clamp 4 comprises a rear bar 5 and a front bar 6. The bar 5 is provided 55 at its upper edge with a jaw 7 and a shoulder 8. The jaw 7 and shoulder 8 extend throughout the entire length of the bar 5, and the shoulder is located forwardly of the jaw and at the lower edge thereof. The front bar 6 60 is provided with a jaw 9, which is offset rearwardly from the bar and extends throughout the entire length thereof. The jaws 7 and 9 are arranged in opposed relation, and the lower edge of the jaw 9 constitutes a shoulder 65 10 which opposes the shoulder 8.

The bars 5 and 6 are secured together by bolts 11 which comprise shanks 12 rotatably mounted in openings 13 extending transversely through the bar 6, outer heads 14 70 contacting with the front side of the bar 6 and provided with finger grips or lugs 15, and externally screw threaded inner heads or blocks 16 contacting with the rear side of the bar 6 and engaged in screw threaded sockets 17 formed in the bar 5 and opening out through the front side thereof. The heads 14 and 16 are diametrically larger than the shanks 12 and serve, by reason of their contact with the front and rear sides of the bar 80 6, to swivelly connect the bolts 11 to this bar. The shanks 12 and heads 16 are made separately to permit the application of the bolts 11 to the bar 6, and after the bolts are applied to the bar these parts are secured together in any suitable manner. As they are swivelly connected to the bar 6, the bolts 11 85 will, when turned in one direction, cause the bars 5 and 6 and jaws 7 and 9 to approach each other and will, when turned in the opposite direction, cause the parts to move away from each other.

In practice the characters necessary to make up the inscription to be chiseled in the monument are selected and applied to the 95 clamp 4 with their tongues 3 positioned between the jaws 7 and 9 and resting upon the shoulder 8, and thereafter the bolts 11 are turned in the direction necessary to effect the clamping of the tongues 3 between the jaws 100

7 and 9. The tongues 3 support the characters above and along the upper edge of the clamp 4, and as they contact with the shoulder 8 they support the characters in proper or horizontal alinement. To enable the characters to be readily arranged in the clamp 4 in proper or uniform spaced relation, the upper beveled edge 18 of the bar 6 is graduated, as at 19.

- 10 After the characters are secured to the clamp 4, they are supported against the monument or the like through the medium of the clamp, and they are outlined or traced on the monument or the like. As it is now outlined on the monument or the like, the inscription may be easily and quickly cut into the monument or the like, and the complete inscription will embody characters of the correct formation and spacing.
- 15 20 From the foregoing description, taken in connection with the accompanying drawing, it will be apparent that the instrument is simple and capable of being manufactured and sold at a comparatively low cost, and that 25 the clamp is of such construction as to permit the characters to be easily and quickly assembled and secured therein.

While we have described the principle of the invention together with the structure 30 which we now consider the preferred embodiment thereof, it is to be understood that the structure shown is merely illustrative and that such changes may be made, when desired, as fall within the scope of the invention as claimed.

We claim:—

- A clamp for blank letters and figures, comprising a rear bar provided at its upper longitudinal edge with a jaw and provided below and forwardly of the body with a shoulder, a front bar resting against the rear bar and provided at its upper longitudinal edge with a rearwardly offset jaw overlying the shoulder and arranged in opposed relation 40 to said first jaw, the jaws being adapted to receive portions of the letters and figures between them and the shoulder being equal in length to the jaws and adapted to support the letters and figures, the rear bar being provided below its shoulder and in its front side with screw threaded sockets, and bolts having shanks rotatably mounted in the front bar and having inner and outer heads contacting with the inner and outer sides of said 45 bar, the inner heads being screw threaded and engaged with said sockets, and the outer heads being provided with finger grips.

In testimony whereof we hereunto affix our signatures.

60 WILLIAM H. WATTS.
ELMER J. CURRIE.
